Primary Examiner — Antoine D Davis(74) *Attorney, Agent, or Firm* — Saidman DesignLaw Group, LLC(57) **CLAIM**

We claim the ornamental design for a control device, as shown and described.

DESCRIPTION

FIG. 1 is a perspective view of a control device showing our new design.

FIG. 2 is a front view thereof.

FIG. 3 is a left side view thereof.

FIG. 4 is a right side view thereof.

FIG. 5 is a top view thereof; and,

FIG. 6 is a bottom view thereof.

The rear view forms no part of the design and is omitted. The portions of the drawings appearing in broken lines are for environment only and do not form part of the claimed design.

1 Claim, 4 Drawing Sheets---
